UNITED STATES PATENT OFFICE.

PAUL DAIMLER, OF CANNSTATT, GERMANY, ASSIGNOR TO DAIMLER MOTOREN GESELLSCHAFT, OF UNTERTÜRKHEIM, GERMANY, A FIRM.

EXPLOSION-MOTOR.

1,016,675.

Specification of Letters Patent.

Patented Feb. 6, 1912.

Application filed June 13, 1911. Serial No. 632,881.

To all whom it may concern:

Be it known that I, PAUL DAIMLER, a subject of the King of Wurttemberg, and resident of 87 Waiblingerstrasse, Cannstatt,

5 in the Kingdom of Wurttemberg, Germany, have invented certain new and useful Improvements in or Relating to Explosion-Motors, of which the following is a specification.

10 This invention relates to the particular arrangement of the sparking device for explosion motors particularly intended for aeronautical vehicles and also to the arrangement of the cold water pump and oil-pump.

15 Hitherto it has been usual to arrange the sparking device laterally of the motor, the driving spindle of the sparking device being arranged parallel to the motor shaft. This arrangement has the disadvantage that special drive is required for the sparking device and that the surface exposed to the resistance of the air during the travel of the vehicle is increased owing to the sparking 20 device projecting laterally from the motor. It has also hitherto been usual to arrange the water pump and oil pump at the side of the motor casing and operate them each by special drive, the driving spindles of the 25 pumps being also arranged parallelly to the motor shaft. Such an arrangement possesses the same disadvantages as that of the laterally arranged sparking device.

According to the present invention the 30 hereinbefore mentioned deficiencies are obviated by arranging the sparking device at one end of the motor with its driving spindle vertical and driven directly from the motor shaft through suitable bevel gear. The

35 sparking device, water pump and oil-pump are preferably arranged one above another at one end of the motor and mutually driven from the motor shaft, the water pump being preferably arranged in the middle with its

40 driving spindle in alinement with the motor shaft and capable of being directly coupled therewith, while the spindles of the sparking device and oil pump are arranged vertical and driven from the motor shaft through

45 50 suitable bevel gear. By this arrangement the surface exposed to the resistance of the air is not increased as there is no projection beyond the side of the motor.

In order that the invention may be more

clearly understood, reference is made to the 55 accompanying drawings, which show by way of example the preferred method of carrying out the invention.

Figure 1 is a detail side view showing the location of the water pump, sparking device and oil pump relatively to the motor, and Fig. 2 is a front view of the same.

Arranged in front of or behind the motor is the water pump *b*, the driving spindle *c* of which is arranged in alinement with 60 the motor shaft *a*. The sparking device *d* is arranged above the water-pump with its driving spindle *f* vertical, and below the water pump is located the oil pump or lubricating device *g* which is likewise arranged with its driving spindle *h* vertical. The oil pump can of course be arranged 65 above the water pump and the sparking device below the same. The spindle *c* of the water pump carries a bevel wheel *i*, which 70 gears with gear wheels *k* and *l* on the ends of the spindles *f* and *h* respectively, the bevel wheel *i* or spindle *c* being capable of being directly coupled with the motor shaft 75 *a* so that the water pump, sparking device 80 and oil pump can be simultaneously driven from the motor shaft. The vertical spindles of the sparking device and oil-pump must of course be arranged in bearings 85 which take up radial and axial thrusts as indicated on the drawings.

The apparatus as shown on the drawings has been arranged in the middle of the end surface of the motor casing, the longitudinal axis of the motor passing through the 90 plane indicated by the line A—B in Fig. 2.

The hereinbefore described arrangement has the advantage that owing to the absence of the hitherto usual individual drive for the different apparatus, the safe driving of 95 the motor is insured, while owing to the absence of lateral brackets for the apparatus the weight of the motor is decreased and owing to the arrangement of the apparatus at one end of the motor the surface exposed 100 to the resistance of the air is decreased as compared with the heretofore usual arrangement.

I claim:

1. In combination with an explosion motor, a sparking device, a cooling water pump and an oil pump, each arranged at one end of the motor and one above another, and

means whereby said sparking device, water-pump and oil-pump may be mutually and directly driven from the motor shaft.

2. In combination with an explosion motor, a sparking device, a cooling water pump and an oil pump, each arranged at one end of the motor and one above another, said water pump being arranged with its driving spindle in axial alinement with the motor shaft, and means whereby said sparking device, water-pump and oil-pump may be mutually and directly driven from the motor shaft.

3. In combination with an explosion motor, a sparking device, a cooling water pump and an oil-pump, each arranged at one end of the motor and one above another, said water pump being arranged with its driving spindle in axial alinement with the motor shaft, and the said sparking device and oil-pump and the driving spindles thereof being arranged vertically, and means whereby said

sparkling device, water-pump and oil-pump may be mutually and directly driven from the motor shaft.

25

4. In combination with an explosion motor, a sparking device, a cooling water pump and an oil-pump, each arranged at one end of the motor and one above another, said water pump being arranged with its driving spindle in axial alinement with the motor shaft, and the said sparking device and oil-pump and the driving spindles thereof being arranged vertically, gearing intermediate the spindle of said water-pump and 30 the spindles of said oil-pump and sparkling device and means for coupling the spindle of the water pump with the motor shaft.

30

In witness whereof I have hereunto set my hand in the presence of two witnesses.

PAUL DAIMLER.
